UNITED STATES PATENT OFFICE.

WALTER S. COLES, OF CINCINNATI, OHIO.

DESIGN FOR A WHIST-TRAY.

SPECIFICATION forming part of Design No. 29,004, dated July 5, 1898.

Application filed January 20, 1898. Serial No. 667,346. Term of patent 7 years.

To all whom it may concern:

Be it known that I, WALTER S. COLES, a citizen of the United States, residing in Cincinnati, in the county of Hamilton and State 5 of Ohio, have invented a certain new and useful Design for Whist-Trays, of which the following is a full, clear, and exact description, reference being had to the accompanying drawings, forming part of this specification.

10 In the drawings, Figure 1 is a perspective view of my design for a whist-tray, and Fig. 2 is a sectional view thereof.

As shown therein, the leading feature of my design consists of a rectangular case made

up of top *a*, bottom *b*, and sides and ends *c c* 15 and formed with compartments *d d*. The compartments are separated from each other by the partitions *f f*.

Having thus described my invention, what I claim, and desire to secure by Letters Patent, is—

The design for a whist-tray, substantially as herein shown and described.

WALTER S. COLES.
